UNITED STATES PATENT OFFICE.

LURA SHORE, OF BELLE PLAINE, KANSAS.

QUILTING-FRAME.

1,163,378.

Specification of Letters Patent.

Patented Dec. 7, 1915.

Application filed March 13, 1915. Serial No. 14,164.

To all whom it may concern:

Be it known that I, LURA SHORE, a citizen of the United States, residing at Belle Plaine, in the county of Sumner and State of Kansas, have invented certain new and useful Improvements in Quilting-Frames, of which the following is a specification.

This invention relates to devices for holding materials to be quilted, and its object is 10 to provide a simple and easily adjustable device of this kind embodying certain novel features of construction to be hereinafter described and claimed.

In order that the invention may be better 15 understood, reference is had to the accompanying drawing, in which—

Figure 1 is a plan view of the device; Fig. 2 is an end view thereof and Fig. 3 is a cross-section on the line 3—3 of Fig. 1.

20 Referring specifically to the drawing, the supporting stand of the device comprises two pairs of laterally spaced legs 5 which are connected by a cross rod 6. The members of the respective pairs of legs are crossed and pivotally connected by the rod 6, the stand being thus similar to an ordinary sawbuck. The ends of the rod 6 are threaded to receive nuts 7 between which the legs are located. The upper ends of the legs 25 are widened and provided with circular bearing openings 8 from which extend straight slots 9 opening through the top edges of the legs. The rollers on which the material is wound are journaled in these 30 openings.

Each roller comprises a flat bar 10 of a thickness to pass freely through the slot 9, and having a width to turn freely in the opening 8. From one of the longitudinal 40 edges of the bar projects a flange 11. This flange terminates short of the ends of the bar so that the latter may enter the bearing openings 8. Operating in conjunction with the bar 10 is a clamping bar 12 having 45 at one of its longitudinal edges an outstanding flange 13 at the same angle as the flange 11, and of the same length. The end of the material 14, shown dotted in Fig. 1, is placed between the two bars and the flanges there- 50 of, and clamped therebetween by spring clips 15 straddling the outer edges of the flanges. The flange 13 is slightly shorter than the bar 12, which permits the applica- 55 tion of spring clips 16 to the end portions of the bars 10 and 12 outside the opposite

edges of the material. By means of these clips the material is securely clamped on the roller, and it can be easily and quickly fastened thereto and unfastened. Both rollers are constructed, and each end of the material is clamped, as hereinbefore described. The legs 5 are adjustable lengthwise on the cross rod 6 according to the width of the material to be quilted, adjustment being readily effected by means of the nuts 7. 60

The ends of the bars 10 project from the bearing openings 8, and in said projecting ends are apertures 17 to receive the down-turned ends of brace bars 18 extending between and connecting the two bars, said 65 ends being threaded to receive nuts 19 for securing the brace bars. By means of the brace bars the legs 5 are prevented from collapsing, and the supporting stand is securely held set up. The brace bars also hold the 70 rollers from turning, but upon removing the same the rollers can be turned to wind or unwind the material 14, and the rollers can also be taken off and the legs folded up for convenience in shipment and storage. 75

I claim:

A quilting frame comprising laterally spaced pairs of legs having circular bearing openings in their upper ends and straight slots extending from said openings through 80 the top edges of the legs, the members of said pairs of legs being connected, rollers journaled in the bearing openings, each of said rollers comprising a flat bar of a thickness to pass through the slot of the bearing, 85 and of a width to turn in the bearing, said bar projecting at its ends from the bearing openings, and having intermediate its ends an outstanding flange at one of its longitudinal edges, said flange terminating short 90 of the legs, a clamping bar opposite the aforesaid bar and terminating short of the legs, said clamping bar having an outstanding flange opposite the first-mentioned 95 flange, means for clamping the bars together, the aforesaid projecting ends of the bars having apertures, and braces extending between said ends of the bars and secured in the apertures therein.

In testimony whereof I affix my signature in presence of two witnesses.

LURA SHORE.
